UNITED STATES PATENT OFFICE.

ERICH LANGGUTH, OF NEERPELT, BELGIUM.

ELECTROMAGNETIC SEPARATOR.

1,076,213.

Specification of Letters Patent.

Patented Oct. 21, 1913.

Application filed April 26, 1912. Serial No. 693,361.

To all whom it may concern:

Be it known that I, ERICH LANGGUTH, engineer, a subject of the German Emperor, residing at Neerpelt, Belgium, have invented certain new and useful Improvements in Electromagnetic Separators; and I do hereby declare the following to be a full, clear, and exact description of the invention, such as will enable others skilled in the art to which it appertains to make and use the same.

This invention relates to an electromagnetic separator for separating ore suspended in water and comprises a stationary induction body, the separating surface of which represents a closed ring relatively to which a multipolar system of magnets is rotatable. Owing to the rotation of the magnetic system within or above the ring, maxima and minima of magnetic attraction are produced on its surface, while the material to be separated is simultaneously transferred to the induction body by means of channels which participate in the rotation.

A construction according to this invention is illustrated in the accompanying drawings in which,

Figure 1 is a vertical section, and Fig. 2 a plan. Fig. 3 is a partial plan view of the apparatus, drawn upon an enlarged scale, with parts omitted; Fig. 4 is a partial vertical section on line U—V of Fig. 3, and Figs. 5 and 6 are partial views, taken in section on lines W—X and Y—Z respectively of Fig. 3.

The material to be separated passes from a stationary feed hopper J into the rotating annular hopper L, from which outlet branches M lead to the rotating supply channels A. These channels are arranged above the four-pole rotatable magnetic system B, and the material falls from the channels on to the stationary induction ring D having a funnel-shaped inner surface.

The induction ring D is provided in a well-known manner with radial grooves, for the purpose of increasing the area of the surface under magnetic influence.

The material passing from the channels A over the induction ring D, is separated below the magnet poles B in such a manner that the diamagnetic material is discharged, while the magnetic material remains adherent to the ring. After a quarter of a revolution the whole circumference of the ring D has been passed by the sup-

ply channels and covered with magnetic material. It is then freed from the material in question by a series of rinsing nozzles H which rotate together with the magnetic system, washing off the magnetic material at the point where the magnetic attraction is a minimum at the moment. The nozzles or ejectors H are supplied with water from an annular tank G, rotating with the magnets B.

In order to prevent the washed-off magnetic material from passing into the same circular collecting channel as the diamagnetic material discharged during the feeding, the rotating magnetic system is provided with a conical sheet-metal tray E which is provided at points corresponding in number to the poles with recesses or outlets R, R', R''. The diamagnetic material can fall through one recess R and arrives at the collector channel K; the washed-off magnetic material passes through another recess or outlet R'' into the collector channel F and the medium material passes through the third recess or outlet R' into a central collector channel N. The material passes from the recesses or outlets R, R', R'' to the collector channels K, N, F, through chutes or spouts O, P, and Q respectively.

The magnetic separator described differs from all well known devices by the separation being effected on a stationary surface, and by the magnetic material remaining at rest on the said surface, until it is washed off by a jet of water at the weakest magnetic point of the magnetic field. Any secondary forces such as centrifugal force and the like, are therefore eliminated such forces coming into play where the separation is effected on a rotary induction tray. These secondary forces exercise an unfavorable effect on the separation, more particularly when substances which have weak magnetic properties are being dealt with. Owing to the suppression of the said secondary forces, and more particularly of centrifugal force, the device according to this invention is specially suitable for those bodies which have only weak magnetic properties.

The number of outer or operative poles in this device can be varied as desired but when it is an even number as shown, I prefer that adjoining operative poles have opposite polarities.

Claims:

1. An electromagnetic separator compris-

- 2
- ing a plurality of magnets held to rotate together and provided with operative poles of alternately opposite polarity, a feed channel held to rotate with said magnets, and a stationary magnetically induced ring located adjacent to the path of the operative magnet poles and adapted to receive the material to be treated, from the said rotary channel.
2. An electromagnetic separator comprising a rotary magnet, a feed channel held to rotate with said magnet, and a stationary magnetically induced ring located adjacent to the path of the operative magnet pole and having an upwardly facing surface adapted to receive and temporarily support the material to be treated, from said rotary channel.
3. An electromagnetic separator, comprising a rotary magnet, a stationary magnetically induced body located adjacent to the path of the operative magnet pole, means for feeding the material to be treated, to said stationary body, and a jet-producing device held to rotate with the magnet and arranged to clear the material from said body.
4. An electromagnetic separator, comprising a rotary magnet, a stationary magnetically induced body located adjacent to the path of the operative magnet pole and having an upwardly facing surface, and means for feeding the material to be treated, to said surface of the stationary body.
5. An electromagnetic separator, comprising a rotary magnet, a stationary magnetically induced body located adjacent to the path of the operative magnet pole, means for feeding the material to be treated, to said stationary body, and means for clearing the material from said body.
6. An electromagnetic separator, comprising a rotary magnet, a stationary magnetically induced body located adjacent to the path of the operative magnet pole, means, held to rotate with the magnet, for feeding the material to be treated, to said stationary body, and means, likewise held

to rotate with the magnet, for clearing the material from the said body.

7. An electromagnetic separator, comprising a rotary magnet, a stationary magnetically induced body located adjacent to the path of the operative magnet pole, means for feeding the material to be treated, to said stationary body, means for clearing the material from said body, and separate collectors for receiving particles of different magnetic behavior.

8. An electromagnetic separator, comprising a rotary magnet, a ring-like stationary magnetically induced body located adjacent to the path of the operative magnet pole and having an upwardly directed surface, means for feeding the material to be treated, to said upwardly directed surface, and means for blowing the material from said surface.

9. An electromagnetic separator, comprising a rotary magnet, a stationary magnetically induced body located adjacent to the path of the operative magnet pole and having an upwardly directed surface, means, held to rotate with the magnet, for feeding the material to said upwardly directed surface, and additional means for clearing the material from said surface.

10. An electromagnetic separator, comprising a rotary magnet, a stationary magnetically induced body located adjacent to the path of the operative magnet pole and having an upwardly directed surface, means, held to rotate with the magnet, for feeding the material to said upwardly directed surface, and additional means, likewise held to rotate with the magnet, for blowing the material from said surface.

In testimony whereof, I have signed this 85 specification in the presence of two subscribing witnesses.

ERICH LANGGUTH.
